[57] **CLAIM**

The ornamental design for an earplug dispenser, as shown and described.

DESCRIPTION

FIG. 1 is a front elevation view of a dispenser, showing my design;

FIG. 2 is a left side elevation view thereof, the right side being a mirror image thereof;

FIG. 3 is a rear elevation view thereof;

FIG. 4 is a plan view thereof;

FIG. 5 is a bottom view thereof; and,

FIG. 6 is a top, front, and left side perspective view thereof, the bottom catch pad being shown in broken lines for illustrative purposes only and forming no part of the claimed design.
